UNITED STATES PATENT OFFICE.

EMIL THEODORE PALMENBERG, OF NEW YORK, N. Y., ASSIGNOR TO J. R. PALMENBERG'S SONS, INC., OF NEW YORK, N. Y., A CORPORATION OF NEW YORK.

DESIGN FOR A PEDESTAL OR THE LIKE.

Application filed March 14, 1927. Serial No. 21,140. Term of patent 7 years.

To all whom it may concern:

Be it known that I, EMIL T. PALMENBERG, a citizen of the United States, and a resident of the city of New York, borough of Manhattan, in the county and State of New York, have invented a new, original, and ornamental Design for Pedestals or the like, of which the following is a specification, reference being had to the accompanying drawing, forming part thereof.

I claim:

The ornamental design for a pedestal or the like, as shown.

EMIL THEODORE PALMENBERG.
